UNITED STATES PATENT OFFICE.

WILLIAM W. WESTON, OF WESTON, SOUTH CAROLINA.

HAY-PRESS.

SPECIFICATION forming part of Letters Patent No. 692,952, dated February 11, 1902.

Application filed August 21, 1901. Serial No. 72,844. (No model.)

To all whom it may concern:

Be it known that I, WILLIAM W. WESTON, a citizen of the United States, residing at Weston, in the county of Richland and State of South Carolina, have invented a new and useful Hay-Press, of which the following is a specification.

My invention is an improved press for baling hay and other substances; and it consists in the peculiar construction and combination of devices hereinafter fully set forth and claimed.

One object of my invention is to effect improvements in the construction of the press-box by providing the same with a pivoted door, which forms the upper side thereof, and by extending the sides of the press-box above the door for a suitable distance, the function of the door being to pack the hay in the press-box prior to the operation of the plunger in compressing the hay into a bale.

A further object of my invention is to provide means for automatically opening the packing-door as the plunger is retracted and for automatically disengaging the packing-door as the plunger reaches the limit of its outstroke to cause the packing-door to fall upon the hay thrown into the press-box to pack the same therein prior to the instroke of the plunger, which compresses the hay into a bale.

A further object of my invention is to effect improvements in the power mechanism which operates the plunger.

In the accompanying drawings, Figure 1 is a perspective view of a baling-press constructed in accordance with my invention. Fig. 2 is a side elevation of the same, showing the reverse side of the press. Fig. 3 is a partial top plan view showing the power mechanism. Fig. 4 is a detail sectional view showing a portion of the rear end of the press-box, the packing-door, and the catch which locks the packing-door when closed. Fig. 5 is a similar view showing the catch which locks the side door when closed. Fig. 6 is a detail top plan view of the outer end or head of the plunger-bar, showing the sheave carried thereby for engaging the packing-door-operating cord and the tappet to disengage said cord from said sheave.

In the embodiment of my invention I pro-

vide a pair of parallel sills 1, which are connected together by cross-bars 2, 3, 4, 5, and 6, disposed on the upper sides thereof, as shown in Fig. 1. The cross-bars 4 5 have their ends projecting for some distance beyond the outer sides of the sills. The press-box 7 is horizontally disposed and is supported on the cross-bars 3 4 5 6. The front end of the press-box is open. The rear end thereof is closed, and the press-box is provided on one side at its rear end with a door 8, which is pivotally mounted at its lower side, as at 9, whereby the said door

may be opened outwardly to a horizontal position to enable a bale to be removed from the press-box. The said door has a bar 10 on its outer side at its upper end, which bar when the door is closed to a vertical position may be engaged by a catch 11, which is pivoted to a bracket 12, that is bolted to the side of the press-box. The said catch has a shoulder 13, which engages the bar 10 when in locking position, as shown in Fig. 5. The ends of the said bar 10 when the door 8 is closed bear against studs 14 on the side of the press-box. Braces 15 connect the ends of the cross-bars 4 5 to studs on the sides of the press-box to strengthen the latter and enable it to withstand lateral stress. The rear portion of the side of the press-box opposite the door 8 is provided with slots 16, which are horizontally disposed and of which there are a suitable number, and the rear end of the press-box is also provided with similar slots. The said slots, as will be understood, enable the wires which are usually employed for fastening the bales to be placed around the bales in the press-box.

Between the vertical sides of the press-box is disposed the packing-door 17, the same being pivotally mounted between the vertical sides of the press-box at the inner end of the latter, as at 18, and it will be observed by reference to Fig. 1 of the drawings that the said sides of the press-box extend above said packing-door when the latter is closed in a horizontal position in the press-box. When thus closed, the rear end of the said packing-door bears on the closed rear end 19 of the press-box. I provide a catch 20 to lock the said packing-door 17 when thus closed. The said catch has its lower end pivoted to a bracket 21 on the rear end 19 of the press-box and has at a suitable distance from its pivotal point

a projecting shoulder 22, which when said catch 20 is in a vertical position overlaps and locks the free rear end of said packing-door 17. The said catch 20 has a handle 23, by 5 which it may be readily operated to lock or unlock the door 17, and the catch 11 is provided with a similar handle 24. It will be understood that by reason of the vertical sides of the press-box being extended above the packing-door the capacity of the press-box exceeds that of the baling-chamber thereof, which constitutes the space between the sides and bottom of the press-box and the packing-door 17 when the latter is closed, and hence 10 when said packing-door is open and hay is thrown into the press-box in a sufficient quantity to fill the same said packing-door when lowered will serve to pack the hay in the baling-chamber prior to the in or compressing 15 stroke of the plunger.

On one side of the press-box are secured a pair of horizontal longitudinally-disposed beams 25, which are disposed one above the other at a suitable distance apart, and the 20 said beams project beyond the inner open end of the press-box. A pair of obliquely-disposed beams 26 are secured to the inner end of the press-box at the side opposite the beams 25, and the said beams 26 converge 25 and are secured to said beams 25, as shown in Figs. 1 and 3. In bearings in the meeting ends of the beams 25 26 is mounted the vertical axle 27 of a cam-drum 28, which is substantially of semi-ovoidal form, the axle 27 being near the inner end thereof, and hence 30 the periphery of the said cam-drum is eccentric to the said axle 27. The said cam-drum is provided with a suitable sweep-lever 29, to which the horse or team may be attached, 35 and the said cam-lever is mounted for partial rotation in reverse directions.

A vertical bar 30 has its lower end secured to the cross-bar 2 at a suitable distance from the inner end of the press-box, and the said 40 vertical bar is secured to the beams 26 and is braced by diagonally-disposed bars 31, between which a pair of direction-sheaves 32 33 are mounted for rotation. At the upper end of the vertical bar is mounted a direction-sheave 34, and at the lower end thereof is a block 35^a, in which is mounted a direction-sheave 35. An operating-cord 36 is attached to the packing-door 17, as at 37, passes over the direction-sheave 34, engages the inner 45 side of the sheave 35, and the said cord has its lower end secured to a longitudinally-disposed inclined beam 38 or other fixed point. The said inclined beam 38 is secured to the cross-bars 2 3 and projects outwardly from 50 the inner end of the press-box, as shown.

A plunger 39 is disposed in the press-box and is adapted to reciprocate therein. To one side of the plunger is pivotally connected the inner end of a plunger-bar 40, which is 55 here shown as comprising an upper section 41, a lower section 42, and a head 43, which connects the said sections at the outer end of

the plunger-bar. On one side of the said head is a sheave 44, and the operating-cord 36 is disposed in the path of the said sheave, 60 so that as the plunger moves on its outstroke the said operating-cord is engaged by the said sheave 44, and thereby the packing-door 17 is opened from the upper side of the press-box to uncover the press-box and enable the 65 same to be filled with hay to form another bale. I also employ a division-block 45, which operates in the press-box in coaction with the plunger. In the sides of the press-box are springs 46, which engage the said division-block and lock the latter against a bale which has been pressed prior to the removal of the bale, and while the plunger is in its outstroke. The operating-cord 36 is provided at a 70 suitable point with a trip 47, which forms a cylindrical enlargement on the said operating-cord, and when the latter has been drawn by the sheave 44 a sufficient distance to raise the packing-door 17 in nearly a vertical position said trip engages a tappet 48 on the head 43 of 75 the follower-bar 40 and is caused by said tappet to disengage the bight of the operating-cord 36 from said sheave 44 automatically, and hence the packing-door 17 is caused by its own weight to fall upon the loose hay in the 80 press-box between the follower and the division-block and pack the hay prior to the ensuing in or compressing stroke of the follower.

The volute periphery of the cam-drum 28 is provided with grooves 49 50. A compressing-cord 51 is attached to the cam-drum at its outer end, is adapted to be wound in and unwound from the groove 49, passes around the sheave 32, and is attached to the head of the follower-bar 40. It will be understood that 85 when the cam-drum is moved in the direction indicated by the arrow in Fig. 3 the same will cause the said compressing-cord 51 to move the plunger or follower inwardly in the press-box to press the hay therein into a bale. It 90 will be further understood that owing to the volute form of the periphery of said cam-lever and the eccentric disposition of the axle 27 of the cam-drum the said plunger will be moved with comparative rapidity initially on 95 its in or compressing stroke and thereafter with constantly-decreasing speed and a corresponding increase of power as the plunger reaches the limit of its compressing stroke. Hence the draft on the horse or team is not 100 increased as the density of the bale increases.

A retracting-cord 52 is attached to the cam-drum, as at 53, is adapted to be wound in and unwound from the groove 50, engages one side of the sheave 33, and is attached to the 105 plunger-bar 40 near the inner end of the latter, as shown. It will be understood that the compressing and retracting cords are reversely disposed on the cam-drum, so that one will be wound thereby while the other is 110 paid out or unwound therefrom, and hence by moving the cam-drum successively in reverse directions the plunger will be caused to move inwardly and outwardly in the press-

box. While I have herein used the term "cords" as applied to the elements 36, 51, and 52, it will be understood that in practice the same may be wire cables, chains, or any 5 other suitable flexible connecting elements.

In order to cause the retracting-cord to be disposed and wound in the groove 20 of the cam-drum on the reverse strokes of the latter, I provide a traveling pulley 54, around which 10 the said retracting-cord passes, which pulley is carried by a swinging arm 55, that moves in an arc concentric with the pulleys 32 33. The said pulley 54 engages and travels in said 15 groove 50 and keeps the retracting-cord in engagement with the said groove.

Having thus described my invention, I claim—

1. The combination with a press-box and a reciprocating plunger, of a cam-drum mounted for partial rotation in reverse directions, 20 reversely-disposed compressing and retracting cords connecting said cam-drum to said plunger, to impart reciprocating movement to the latter, direction-sheaves engaged by 25 said cords, and a traveling pulley, bearing on said cam-drum and around which said retracting-cord passes, substantially as described.

2. In a press, the combination of a press- 30 box, a pivotally-mounted packing-door, a reciprocating plunger, an operating-cord connected to said door, said plunger having an engaging element in the path of which said operating-cord is disposed, whereby said cord 35 is caught by said engaging element, on the outstroke of the plunger, to raise said packing-door, said operating-cord and an element of said plunger having coacting trip elements to release said cord from said engaging ele- 40 ment, for the purpose set forth, substantially as described.

3. The combination of a horizontally-dis- 45 posed press-box having a packing-door adapt-

ed to be raised and lowered to open and close the upper side of the box, a plunger in the latter, means to operate the plunger, an operating-cord to open said packing-door, a trip on said cord, means, carried by said plunger-bar, to engage and draw said cord and open said packing-door, on the outstroke of said plunger, and a tappet, carried by said plunger to coact with said trip to release said cord from said engaging means and thereby permit said packing-door to drop to a closed position prior to the ensuing instroke of the plunger, substantially as described.

4. In a baling-press, a horizontally-disposed press-box having its outer end closed, its upper side open, a door in one of its sides, at the outer end thereof, and a packing-door to close the open upper side thereof, said packing-door when closed extending from end to end of the press-box and being hinged at one end to the inner end of the press-box, in combination with a plunger, operative in said press-box, means, actuated by said plunger to raise said packing-door on the outstroke of the plunger, and release said door when raised, so that the said packing-door will fall by its own weight prior to the compressing 70 instroke of the plunger, and means to lock said packing-door and side door, when closed, said side door permitting the removal of the bales and said closed outer end of the press-box coacting with the sides and bottom 75 thereof and with the packing-door and plunger to compress the bales, substantially as described.

In testimony that I claim the foregoing as my own I have hereto affixed my signature in 80 the presence of two witnesses.

WILLIAM W. WESTON.

Witnesses:

O. M. DOUGLAS,
J. N. RAWLINSON.
